UNITED STATES PATENT OFFICE.

DAISY OSTENBERG, OF SAN JOSE, CALIFORNIA.

DESIGN FOR A DOLL.

54,766.

Specification for Design.

Patented Mar. 23, 1920.

Application filed August 26, 1919. Serial No. 320,072. Term of patent 7 years.

To all whom it may concern:

Be it known that I, DAISY OSTENBERG, a citizen of the United States, residing at San Jose, in the county of Santa Clara and State of California, have invented a new, original, and ornamental Design for Dolls, of which the following is a specification, reference being had to the accompanying drawing, forming a part thereof.

In the drawing:—

Figure 1 is a side elevation of the doll, showing my new design.

Fig. 2 is a front elevation of the same.

I claim:

The ornamental design for a doll, substantially as shown.

DAISY OSTENBERG.
